LOUIS B. GIRARD, OF LOS ANGELES, CALIFORNIA, ASSIGNOR TO THE GIRARD MANUFACTURING COMPANY, OF LOS ANGELES, CALIFORNIA, A CORPORATION OF CALIFORNIA.

STAPLE.

1,163,140.

Specification of Letters Patent.

Patented Dec. 7, 1915.

Application filed February 3, 1914. Serial No. 816,151.

To all whom it may concern:

Be it known that I, LOUIS B. GIRARD, a citizen of the United States, residing at Los Angeles, in the county of Los Angeles and State of California, have invented a new and useful Staple, of which the following is a specification.

This invention relates to a particular form of staple, and one of the objects of the invention is to provide a staple with prongs having the edges of the points of the prongs formed with sharp edges, so as to enable the points of the prongs to be driven easily and accurately into a body and without twisting 15 of the prongs or staple.

Figure 1 is a vertical section of the dies for forming the staple, showing the position in which the staple has been cut and bent at its end portions only. Fig. 2 is a section 20 on line x^2-x^2 in Fig. 1. Figs. 3 and 4 are views similar to Figs. 1 and 2, respectively, showing the position in which the staple has been severed. Fig. 5 is a perspective of 25 the upper die body. Fig. 6 is a perspective of the base or lower die body. Fig. 7 is a plan view thereof, showing the stock strip. Fig. 8 is a perspective of the form over 30 which the staple is bent. Figs. 9 and 10 are plan views of different length staple blanks 35 made from the same stock strip. Fig. 11 is a cross section of the stock strip. Fig. 12 is a perspective view of the staple.

My improved staple may be made by any suitable means, for example, by the die 40 means shown in Figs. 1 to 8 of the drawing, and comprising a base plate 78 formed with a vertical slot 79 so as to constitute the female die member, a member 80 mounted to slide in member 78, and provided with anvil 45 82; an upper die member 27 provided with vertical prongs 28, adapted to enter said slot on either side of said anvil, and a severing member 29 adapted to slide in a way 27" in member 27, between prongs 28. Base member 78 is provided with a way 50 81 in which the anvil member 80 slides, and with a recess or channel 74 in which the stock strip 48 extends, a guide pin 73 being provided for said stock strip, and a strip 55 per 86 being mounted over the stock strip. A slot 84, for receiving the forward end of the stock strip, is formed in member 80, above the anvil 82, and said member 80 is provided, above said slot, with an inclined 60 face portion 83. I have also shown in Figs.

1 to 4, a work support 20, and a staple 65 clenching die 24 mounted to slide in said work support. Base member 78 may have a die plate 71 forming a cutting member adjacent the slot 79.

The stock strip 48 from which the staples are made, is a flat strip of metal, having each of its edges beveled so as to present a sharp edge, and I prefer to bevel each edge at each side of the strip, as shown in Fig. 12, 65 so that the staple will have the edges of its pointed ends sharpened on both sides. The stock strip 48 is placed in the channel 74, with its forward end in contact with the front face 75 of the slot 79, which serves as 70 a stop therefor, the strip being placed more or less obliquely to said face according to the length of staple to be formed, and being centralized with reference to slot 79 by the guide pin 73 engaging with its outer edge. 75 The die member 27 is moved down, so that its prongs 28 pass on into the vertical slot 79, and cut the stock strip at each side and bend the cut portions down at either side of the anvil 82, this position of the parts being 80 shown in Figs. 1 and 2. The severing member 29 is then brought down, as shown in Figs. 3 and 4, so as to sever the stock strip, 85 between the cuts previously made, and thereby sever the formed staple from the stock strip and by a continuation of the same movement, drive the staple downward out of the die means. With the means herein shown, this movement of the staple drives it into the work, supported on the work holder 90 20, and the die 24 then clenches it, but the present invention relates to the staple as formed by the die means, irrespective of any such driving and clenching operations.

As the stock strip 48 is fed in a direction 95 oblique to the stop face 75 and the cutting edge of the die member 71, it follows that the ends of the severed portion of the strip forming the blank for the staple are inclined or oblique with relation to the length of the strip, as shown in Figs. 9 and 10, so as to form points which will penetrate the paper, wood or other material which is being stapled. The length of the staple between the prongs thereof is determined by the width 100 of the forming projection 84 and the length of the prongs is determined by the excess of length of the blank cut from the stock strip over the width of this forming projection. 105 The length of the blank so cut may be varied 110

so as to provide for longer prongs or pointed ends of the staple in stapling heavier material, by adjusting the angular position of the stock strip. Thus as indicated in Fig. 7, by shifting the stock strip from the full line position to the dotted line position, the length of the blank cut from the end of the strip is increased, as shown by the full and dotted lines. The guide pin 73 serves in 10 this operation to always keep the stock strip centralized with respect to the cutting dies. The slot 79 and prong severing dies 28 working therein are sufficiently wide to cut the prongs in any position to which the 15 stock strip may be adjusted.

The edges of the stock strip are beveled to 20 form a sharp edge on both sides as indicated at 48' in Fig. 11. The result of this is that when the staple is formed there is a sharp 25 tapering edge 48' as shown in Fig. 12 formed on each prong and with sharp points 30 88. In driving the staple the beveled edge 48 cuts into the wood and allows the prong 35

Copies of this patent may be obtained for five cents each, by addressing the "Commissioner of Patents, Washington, D. C."

48 to move straight downward into the wood 25 without being shoved off to one side which is the case where the edge 48' is a simple flat edge as in other forms of staples. In driving the present staple the prongs pass down 30 without being twisted or without the staple being turned from its regular position.

What I claim is:

A staple formed from a flat strip of metal having its ends oblique to the width of the strip so as to form prong points for the staple and having said pointed end portions 35 bent transversely to the middle portion of the staple, the oblique edges of said pointed prong ends being beveled to form sharp edges.

In testimony whereof, I have hereunto set 40 my hand at Los Angeles, California this 26th day of January, 1914.

LOUIS B. GIRARD.

In presence of—

ARTHUR P. KNIGHT,

LORRAINE E. DURROW.
